UNITED STATES PATENT OFFICE.

HARRIS H. HAYDEN, OF NEW YORK, N. Y., ASSIGNOR TO THE AUTOMATIC PARCEL DELIVERY COMPANY, OF SAME PLACE.

STORE-SERVICE APPARATUS.

SPECIFICATION forming part of Letters Patent No. 277,276, dated May 8, 1883.

Application filed March 21, 1882. (No model.)

To all whom it may concern:

Be it known that I, HARRIS H. HAYDEN, of the city, county, and State of New York, have invented certain Improvements in Store-Serv-
55 ice Apparatus, of which the following is a specification.

My invention relates to that class of store-service systems in which traveling hollow carriers move upon ways extending between the
10 main desks and the counters or stations occupied by salesmen; and my invention consists in means for readily placing the carriers upon and removing them from the track, and in a construction whereby the efficiency of the carriers is increased.
15

In the drawings, Figure 1 is an elevation illustrating the construction of the track and means for placing the carriers on the same. Fig. 2 is an inverted plan view of Fig. 1. Fig. 20 3 is an enlarged cross-section on the line 1 2, Fig. 1. Fig. 4 is a plan view, showing appliances for removing the carrier. Fig. 5 is a side view of Fig. 4. Fig. 6 is a perspective view of Fig. 4. Fig. 7 is a longitudinal section of one of the carriers, and Fig. 8 is an end view of the carrier open.

The "way" A in this instance is constructed to support a rolling hollow carrier, and consists of parallel strips *a a*, which may be plain
30 strips, square or oblong in cross-section, or of the more ornamental form shown in Fig. 3, in which each strip is of an L shape, so as to form a side flange, *a'*, and a bearing-face, *x*. These side flanges maintain a cylindrical carrier at
35 right angles to the track and prevent it running diagonally or jamming. These strips are connected together parallel to each other, but sufficiently separated to receive the carriers between them by means of cross-braces *b*, of any
40 suitable form and material, preferably of cast-iron. By this means the way may be constructed of any desired width by simply varying the length of the cross-pieces, and is much lighter, more elastic, and produces with the
45 carrier less noise than the solid structure heretofore used. In some cases the way may be formed of three or more light parallel strips secured to the sides and bottoms of U-shaped cross-braces, and the edges or faces upon which
50 the carriers roll may have felt or rubber bearings.

For the purpose of placing the carriers upon the way constructed as described, or in any other manner, I use pivoted send-off sections C, each set at any desired angle to the way A, 55 one side or flange of which is cut away opposite said section, and the pivot-point *f* is so arranged that the inner end of the section will practically correspond with the way whatever may be the angle of the former. The outer 60 end of the section is closed by the spring *p*, which is bent so as to hold the carrier with a tight pressure in position and prevent it from jumping when the arm is allowed to go up suddenly, and is counterbalanced by suitable appliances—for instance, by a weight, *h*, connected to a cord, *k*, extending over a pulley, *l*—and may be drawn down by a cord, *g*, until within easy reach of the attendant, as shown in dotted lines, Fig. 1, or it may be raised by a 70 spring or otherwise. After the carrier D is placed within the section, as shown in dotted lines, and the cord *g* is released, the weight *h* will carry the section upward to the position shown in full lines, so as to discharge the carrier into the trough with an impetus sufficient, in cases where the way is short, to insure its reaching its destination even without sloping the way, or to give it a good starting impetus in a longer line where the grade will suffice to 75 carry it to the end rapidly.

To prevent the carriers from jumping from the ways, I have for some time used guard rails or wires *e*, supported by standards *d*.

Different appliances may be used for removing the carriers at their stations. I prefer, however, to use a deflector, *W*, (shown in Figs. 4, 5, and 6,) which said deflector is placed at an angle to and extending over the track, so as to be struck by the carrier, which is thus tilted 85 to one side, and falls into a basket, *V*, or other suitable receptacle. To facilitate the removal, the guard or flange opposite to the deflector at *x* may be cut away to a greater or less extent. The deflectors may be set in different positions 90 in respect to graduated balls, so as to discharge each ball at the counter from which it was sent.

The basket or receptacle *V* may be suspended by a cord, *t*, provided with a counterbalance-weight, *u*, and a pendent cord, *w*, serves as a means for hauling down the basket when

necessary. Carriers of various forms may be used upon the ways described; but for the purpose of sending goods as well as cash I prefer to use cylindrical carriers D, which are guided by the flanges a' , the carriers being either divided longitudinally and the two parts hinged together, or provided with movable or hinged ends m , as shown in Figs. 7 and 8.

It is important in using rolling carriers to provide means for holding the goods centrally in the carriers, as any considerable weight falling to one side will prevent them from rolling. Different means of effecting this may be employed—as, for instance, springs secured to the opposite sides, (shown in dotted lines, Fig. 7.) A very simple and effective plan, however, is to use cross-bands $n n$, of rubber or elastic fabric, arranged longitudinally, as in Fig. 7, or transversely, as in Fig. 8. In either case articles placed between the bands will be held centrally in the carrier.

The cash may be put in a cash box or pocket, s , at the head or lid of the carrier, and held by a rubber cross-band, or otherwise.

I do not here claim the way consisting of two parallel strips and cross-pieces.

I claim—

1. The combination of the way, send-off sections C, pivoted thereto at their inner ends, and the counter-balance, for the purpose specified.

2. The combination, with the way, of send-off sections C, pivoted thereto at their inner ends, but arranged in an angle therewith, for the purpose specified.

3. The combination, with the way, of deflectors W, substantially as set forth. 35

4. A carrier for store-service, cylindrical in form, in combination with ways having side flanges, a' , whereby the carrier is maintained at right angles to the way, as set forth. 40

5. A hollow cylindrical carrier for store-service, adapted to roll upon ways thereof, and provided with means, substantially as described, for maintaining the contents in a central position, in combination with ways constructed to receive and guide such carrier, for the purpose specified. 45

6. The combination, with a way of a store-service apparatus and with a throw-off device, of a hanging basket, V, counterbalanced by a weight or spring and provided with a cord, t , and arranged substantially as set forth. 50

In testimony whereof I have signed my name to this specification in the presence of two subscribing witnesses.

HARRIS H. HAYDEN.
